UNITED STATES PATENT OFFICE.

MARTIN AUENSEN, OF CEMENT, CALIFORNIA.

ROTARY GAS-ENGINE.

1,069,516.

Specification of Letters Patent.

Patented Aug. 5, 1913.

Application filed August 5, 1910. Serial No. 575,715.

To all whom it may concern:

Be it known that I, MARTIN AUENSEN, a citizen of the United States, residing at Cement, in the county of Solano and State of California, have invented new and useful improvements in Rotary Gas-Engines, of which the following is a specification.

This invention relates to hydro-carbon engines and particularly to rotary gas or gasoline engines.

The object of the invention is to cause the wings or pistons of the rotor to compress their own charges in a combustion chamber and then actuate a sparking lever to explode the charge thus compressed against the piston.

A further object of the invention is the provision of a rotor carrying a plurality of pistons which are adapted to actuate a combustion chamber valve whereby said valve is forced from its active position to permit the piston to take its place at the time of explosion.

A further object of the invention is the provision of a casing for rotating pistons with means for ventilating the piston throughout its rotation except at the points of compression and explosion.

Further objects of the invention will appear as the following specific description is read in connection with the accompanying drawing which forms a part of this application, and in which:

Figure 1 is a vertical sectional view. Fig. 2 is a similar view showing a different position of the rotor. Fig. 3 is a transverse vertical section. Fig. 4 is an end elevation of the engine. Fig. 5 is a detail vertical sectional view showing a modified form. Fig. 6 is a detail section taken on an irregular line through Fig. 5.

In the specific embodiment of the invention illustrated herein 1 represents the cylindrical rotor casing which is bolted to the side plates 2 and is provided on its inner side with a cam-faced projection 3 having a diagonal end 4 in which is formed a pocket or combustion chamber 5. Journaled in the side plates and passing centrally through the casing is the driving shaft 6 upon the outer end of which is secured a suitable balance wheel 7 and keyed to which is a rotor 8 which is concentrically mounted in the casing and is provided with a plurality of slots 9 in which are mounted the pistons 10. These pistons are constructed of separate

pieces of metal 11 and 12, the former of which is mortised at 13 and the latter of which is provided with a tongue 14 adapted to enter the mortise and be adjustable therein. A suitable spring 15 forces the parts of these pistons outwardly against the side plates so as to provide a tight joint between these parts. The pistons are preferably projected outwardly by means of springs 16 seated in the slots or recesses 9 so that the outer ends of the pistons are brought into engagement with the inner face of the casing 1. Suitable packing 17 is arranged in the ends of the pistons to provide a tight joint between the same and the inner side of the casing.

Secured to the outside of the casing adjacent its top is a bearing bracket 18 in which is slidably mounted a gate valve 19 which passes diagonally through the aperture 20 in the casing and lies alongside of the face 4 of the projection 3 so as to close the combustion chamber 5 until displaced by one of the pistons. The valve 19 is normally pressed against the outer face of the rotor by means of a spring 21 and is adapted to be lowered into a socket 22 formed in the rotor so that the port 23 will register with the slot 24 formed in the valve whereby the combustion chamber may be blown out. The valve 19 closes immediately after the pistons pass the same by the action of the spring 21 which also disconnects the contact parts as will be hereinafter described.

The outer ends of the pistons are cut off as at 25 so as to fit the diagonal face 4 of the projection 3 when they rise from their depressed position which is caused by the cam face of the projection. As these pistons 95 rise to close the combustion chamber 5, the valve 19 is displaced and in rising contacts with a lever 26 which is pivoted upon an arm 27 carried by the bracket 18 and whose end is adapted to be carried into engagement with a sparking rod 28 against the tension of the spring 21. The inlet port in the casing is shown at 29 and the outlet or exhaust port is shown at 30.

In the operation of the device, a suitable 105 quantity of combustible mixture is drawn or forced into the inlet opening at 29 and is compressed into the combustion chamber 5 through a port 31 which is controlled by a check valve 32. As the piston passes the end 110 of the projection 3 and rises under the influence of the spring 16 it displaces the

valve 19 and takes its place, thus maintaining a closed combustion chamber and the compression of the combustible mixture therein. Upon attaining its maximum height 5 the valve 19 operates the lever 26 to contact with the sparking rod 28. This sparking arrangement is not shown complete in itself as it may be of the make and break type controlled by the lever or it may be 10 of the jump spark type and have the circuit completed by the lever. It is sufficient to state that the spark is produced within the combustion chamber at the time of its complete closure by a piston.

15 In order to cool the engine and produce a more efficient mixture therefor, the casing is provided with a plurality of openings 33 which extend at intervals around the same from the exhaust port to the inlet port. The 20 pistons in their travel suck in a quantity of air which tends to cool the engine and a portion of said air is compressed in the combustion chamber, so as to combine with the 25 gases and produce a more efficient mixture.

25 In Figs. 5 and 6 the side members 2 are shown as provided with a slot 34 which is inclined upwardly for a predetermined distance and then is turned downwardly on the 30 arc of a circle which conforms with the periphery of the rotor. The slots taper inwardly at one end and outwardly at the other so as to cause the ready engagement 35 of the lateral pins 35 and their ready disengagement from the slot. These pins are carried by the pistons and are projected into engagement with the slot by springs 36. This arrangement is provided to make a more positive movement of the pistons. The laterally projected pins enter the slots at

the point marked *x* and cause the piston to 40 ride up alongside of the face 4 independent of the action of the springs 16. They then travel in a line concentric with the periphery of the rotor and within the periphery of the casing until they emerge from the slot 45 at the point *y*.

Having thus described the invention, what is claimed is—

1. A rotary internal combustion engine comprising a casing having a combustion chamber therein, a rotor having radially movable pistons to compress the charge within the combustion chamber, and means acting on said pistons to move the same radially for closing the combustion chamber, whereby the charge when exploded will act upon the same to drive the rotor, and a valve for normally closing the combustion chamber which valve is displaced by the pistons. 60

2. In a rotary internal combustion engine, the combination with a casing having an inlet port therein, a combustion chamber formed in the casing, a rotor mounted in the casing, a plurality of radially movable 65 pistons carried by the rotor, means for projecting the pistons across the mouth of the combustion chamber, means for controlling the entrance of the charge to the combustion chamber from the casing, and means displaced by the pistons for normally closing the combustion chamber. 70

In testimony whereof I affix my signature in presence of two witnesses.

MARTIN AUENSEN.
